UNITED STATES PATENT OFFICE.

JOHN CHARTER, OF WHITMAN, MASSACHUSETTS.

VEHICLE.

1,020,636.

Specification of Letters Patent. Patented Mar. 19, 1912.

Application filed May 2, 1910. Serial No. 558,962.

To all whom it may concern:

Be it known that I, JOHN CHARTER, of Whitman, in the county of Plymouth and State of Massachusetts, have invented certain new and useful Improvements in Vehicles, of which the following is a specification.

The present invention relates to vehicles, and its object is to provide novel means of mounting an upper structure, such as a body, upon running gear by spring tension members adapted to maintain the body at substantially one position whenever the wheels of the running gear suddenly rise or fall by reason of striking an obstacle or entering a depression.

The usual method of mounting a body upon running gear is to connect the body directly with the running gear by means of springs which permit the body to rise and fall vertically with relation to the running gear. The result of such direct spring connection when the wheels of the running gear pass over an obstacle or enter a depression is to incline the body to a degree commensurate with the inclination of the running gear. The body is therefore subjected to successive jolts or jounces, and the riding qualities of the body are therefore seriously impaired.

The present invention is carried out by supporting the body upon inclined struts pivotally connected to the running gear and connected to the body by spring tension means adapted to preserve the inclination of the struts and tending to swing the struts upwardly. The struts are preferably arranged in pairs, each pair extending along one of the four sides of the body and beneath the same. The struts which extend along the side edges of the body are preferably attached to the front and rear axles by pivots, those attached to the front axles being also connected to the rear of the body, while those attached to the rear axle are likewise attached to the forward end of the body. By thus connecting the struts, each with one end of the running gear and with the opposite end of the body, the forward part of the running gear serves as a base or support for the rear end of the body, while the rear end of the running gear serves as a base or support for the forward end of the body. Now, therefore, whenever the front wheels of the vehicle are suddenly raised or permitted to drop their vertical movement

is not permitted to affect the forward end of the body, because that end of the body is not supported by the forward end of the running gear but is supported by the rear end of the running gear.

The struts which extend transversely under the forward end of the body, and those which extend transversely under the rear end of the body may be constructed and arranged in the same manner as those which extend longitudinally of the body under the side edges thereof. In this way, the right-hand side of the body is supported by the left-hand side of the running gear, while the left-hand side of the body is supported by the right-hand side of the running gear, consequently the body is supported at all sides by spring tension connections which to a great extent prevent the transmission to the body of sudden upward and downward movements of the wheels.

Referring now to the drawings which illustrate one form in which the present invention may be embodied: Figure 1 represents a side elevation partly in section of the running gear and body of a motor car, the representation being more or less conventional and omitting the usual equipment. Fig. 2 represents a front end elevation partly in section of such motor car. Fig. 3 represents the longitudinal section on a larger scale of a spring tension plunger such as those included in Fig. 1.

The same reference characters indicate the same parts wherever they occur.

Although the drawings illustrate the invention as applying to a motor car, it should be understood that it is not adapted exclusively for a vehicle of this type but that it may be applied to horse-drawn vehicles as well, and that the motor car is selected merely for the purpose of illustration and not for limitation.

On the drawings the body or upper structure of the car is indicated at 10, and the front and rear wheels at 11 and 12 respectively.

13 and 14 indicate respectively the front and rear axles and constitute members of the usual running gear.

It should be understood that no attempt has been made to illustrate all the necessary parts of the running gear, but that only so much of the running gear is illustrated as is necessary in order to make it clear how the body is supported thereby. For the

purpose of present description it is sufficient to state that the front and rear axles and their respective wheels constitute the running gear.

5 15 and 16 indicate a pair of struts extending along one of the longitudinal sides of the body. There will, of course, be a pair of such struts at either side of the vehicle. The struts 15 are pivotally connected at 17 10 to the front axle 13 and are inclined upwardly therefrom toward the rear end of the body. Struts 16 are likewise pivotally connected at 18 to the rear axle and are inclined upwardly toward the forward end of the body. At the upper ends of the struts 15 are yokes or forks 19 which are pivotally connected by studs 20 to plungers 21 and 22. The plungers extend horizontally through cylindric barrels 23 and 24 which 20 are supported by the body. The barrels are provided with bearings 25 and 26 in which the plungers are adapted to slide, the bearings 26 being removable and adjustable by reason of being screw threaded in the barrels. Each plunger is provided with a fixed piston 27, the pistons fitting the interior of the chambers with a fair degree of accuracy so that they are adapted to compress the air in the barrels when they are moved in 30 either one direction or the other.

Each barrel contains a pair of helical springs which are indicated respectively at 28 and 29, the springs 28 being the supporting springs for the body and the 35 springs 29 being recoil springs to cushion the upward movement of the body. The ends of the plungers 21 and 22 where they are pivotally connected with their respective struts may be provided with rollers 30 arranged to roll upon the under surface of plates 31 carried by the body, the purpose of the rolls being to prevent lateral flexure of the plungers due to upward thrust of the struts.

45 Referring now to Fig. 2, 32 indicates a barrel extending transversely of the body directly above the front axle. This barrel may be divided midway between its ends by an abutment 33, thus forming two 50 chambers indicated respectively at 34 and 35. Bearing pieces 36 are screw threaded in the ends of the barrel and are centrally bored to receive plungers 37 and 38. The plungers are pivotally connected at 39 to 55 yokes 40 affixed respectively to the upper ends of the struts 41 and 42 which are inclined upwardly from the right and left ends of the axle. The lower ends of the struts are connected to the axle by pivots 60 43, said struts being crossed in the same relation as the struts 15 and 16 which support the longitudinal sides of the body. The inner ends of the plungers 37 and 38 are provided with pistons 44 which are engaged by supporting springs 45 and 46 on

the one side and by recoil springs 47 and 48 on the other side. The supporting springs are compressed between the pistons and the respective end bearings 36, while the recoil springs are compressed between the pistons and abutment 33. The plungers are provided with rolls 49 which engage the under surface of the plates 50 carried by the body and serve the same purpose as that prescribed for the rolls 30.

70 From the foregoing description it will be apparent that when a wheel suddenly rises or falls by reason of striking an obstacle or entering a depression the corresponding corner of the body will not rise or fall with the wheel but will be supported at its former position by its respective longitudinal and transverse struts. Of course, the body will eventually assume a position approximately parallel to the general plane 80 of the running gear, but it is not subject to constant upward or downward movement unless all of the wheels of the vehicle rise and fall at the same time.

85 The movement of the body is cushioned 90 not only by the several springs but also by the cushions of air in the several barrels.

The barrels may be provided with vents as shown by Fig. 3 and with throttling members to restrict the vents to the desired 95 capacity. In Fig. 3 a nozzle is indicated at 51, said nozzle being formed upon the barrel 24 and provided with a bore through which air may be expelled to the atmosphere or through which it may be drawn in. 52 indicates a screw-threaded throttling member by which the vent may be opened or closed to the desired capacity. The barrel may also be provided with a vent 53 through 100 which air may enter or leave the chamber on the opposite side of the piston 27.

If desired, each of the piston chambers may be provided with vents such as those described, and all or any of such vents may be provided with throttling members such as that indicated at 52.

110 Not only may the cushioning effect of the air within the chambers be increased or decreased but the tension of the several springs may also be increased or decreased.

115 The adjustment of the spring tension may be effected by the screw-threaded members 26 of the longitudinal barrels and by the members 36 of the transverse barrels.

120 The rear end of the body is provided with supporting means like that described for the forward end of the body.

Having thus explained the nature of my said invention and described a way of constructing and using the same, although without attempting to set forth all the forms in which it may be made or all the modes of its use, what I claim is:

125 A vehicle comprising a running frame; a pair of longitudinally-extending struts at 130

each side thereof, one strut of each pair being pivotally connected to the forward part of the running frame and inclining upwardly toward the rear, the other struts 5 being pivotally connected to the rear part of the running frame and inclining upwardly toward the front and crossing those connected to the front; two transversely extending struts pivotally connected to one 10 side of the running frame at the front and rear respectively and inclining upwardly toward the other side; two transversely-extending struts pivotally connected to the other side of the running frame at the front 15 and rear respectively and inclining up-

wardly in the opposite direction so as to cross the first-mentioned transverse struts; the free ends of said longitudinal struts being close to the free ends of said transverse struts over the corners of the running 20 frame; spring-tension means acting on said struts for keeping their free ends up; and a body resting on said free ends but otherwise unsupported.

In testimony whereof I have affixed my 25 signature, in presence of two witnesses.

JOHN CHARTER.
